UNITED STATES PATENT OFFICE.

WILSON E. PORTER, OF NEW HAVEN, CONNECTICUT, ASSIGNOR TO NEW HAVEN CLOCK COMPANY, OF NEW HAVEN, CONNECTICUT, A CORPORATION.

RATING DEVICE FOR TIMEPIECES.

No. 832,339.

Specification of Letters Patent.

Patented Oct. 2, 1906.

Application filed March 25, 1905. Serial No. 251,931.

To all whom it may concern:

Be it known that I, WILSON E. PORTER, a citizen of the United States, residing at New Haven, in the county of New Haven and State of Connecticut, have invented a new and useful Improved Rating Device for Timepieces; and I do hereby declare the following, when taken in connection with the accompanying drawings and the figures of reference marked thereon, to be a full, clear, and exact description of the same, and which said drawings constitute part of this specification, and represent, in—

Figure 1, a view in front elevation of one form which my improved device for rating timepieces may assume as it appears with a timepiece to be rated applied to it; Fig. 2, a corresponding view with the timepiece to be rated removed; Fig. 3, a plan view with the timepiece to be rated removed; Fig. 4, an enlarged broken view of the upper right-hand portion of the front frame-plate of the device with the dial of the standard timepiece removed without, however, removing the rated or the rating pointer; Fig. 5, a plan view thereof including the dial; Fig. 6, an enlarged view of the upper right-hand portion of the rear frame-plate of the device, showing the means employed for restoring the three pointers to their starting or zero positions. Fig. 7, a broken view in vertical section on the line *a b* of Fig. 4, but showing the restoring-slide in elevation; Fig. 8, a view in front elevation of one of the modified forms which my improved device may assume; Fig. 9, a plan view thereof; Fig. 10, a detached view in front elevation of the rear frame-plate thereof, showing its restoring-slide; Fig. 11, a broken plan view of the left-hand end of the device, drawn on an enlarged scale and showing a timepiece applied to the device in position for rating, the said timepiece having its running parts removed, except the single wheel, which is meshed into by the wheel 33 of the rating device; Fig. 12, a detached view, in front elevation on an enlarged scale, of the plate 32 of the timepiece-holder, showing also the locking-lever, by means of which the timepiece to be rated is secured to the said plate; Fig. 13, a broken sectional view on the line *a b* of Fig. 12, showing the engagement of the spring-finger 48 of the locking-lever with the rear movement-plate of the timepiece; Fig. 14, a sectional view on the

line *c d* of Fig. 12, showing the engagement of the rear movement-plate of the timepiece with the locking-finger 45 of the locking-lever; Fig. 15, a detached view, drawn to natural size, of the plate of the timepiece-holder; Fig. 16, a sectional view thereof on the line *e f* of Fig. 15.

My invention relates to an improved device for rating watches and clocks of the so-called "marine" type, the object being to produce a simple and convenient mechanism by which such timepieces may be quickly and accurately rated instead of rating them either by eye or ear, according to the common practice, whereby time and labor are saved and whereby rating may be done by a person relatively unskilled as compared with the skill of an expert "timer" who becomes adept only by long and extensive experience.

With these ends in view my invention consists in a rating device having certain details of construction and combinations of parts, as will be hereinafter described, and pointed out in the claims.

As shown in Figs. 1 to 7, inclusive, I mount a standard timepiece of any approved construction between a front frame-plate 2 and a corresponding back frame-plate 3, united by pillars 4, receiving screws 5. The said standard timepiece may be of any approved construction, and therefore it is unnecessary to either illustrate or describe it in any detail. As shown, it consists of a watch-movement having a front movement-plate 6, a back movement-plate 7, pillars 8, and screws 9, passing through the said plates and entering the ends of the pillars. This timepiece is secured to the inner face of the front frame-plate 2 by means of three screws 10, Figs. 1 and 2. As herein shown, the movement of the fourth wheel 11, Fig. 4, of the train of the timepiece is transmitted to a small wheel 12, mounted on an arbor 13, journaled in the frame-plates 2 and 3 and also carrying a relatively large wheel 14, meshing into a pinion 15, mounted on a shaft 16, also journaled in the said frame-plates 2 and 3 and projecting at its forward end through the plate 2 and through a rated dial 17, secured by screws 18 to the outer face thereof, and carrying a pointer 19, which sweeps over the said dial synchronously with the action of the standard timepiece. This pointer I shall hereinafter speak of as the "rated" pointer for the reason that it indi-

cates the action of the standard timepiece. For convenience, as well as for accuracy, the wheels and pinions employed to drive the rated pointer 19 by preference will be constructed and arranged so that the pointer will make a revolution of the dial once in a few seconds—say, once in five or ten or fifteen seconds. Of course the wheels and pinions might be arranged to make the pointer sweep the dial only once a minute; but obviously the more rapidly the rated pointer moves the more striking and easily observed the variations between the rate of the two timepieces, nor is it necessary that the movement of the standard timepiece be taken from the fourth wheel thereof, as shown, though probably it will be found most convenient to utilize the said fourth wheel for the purpose. In order to permit the rated pointer 19 to be restored at will to its starting or zero position, in which it registers with the twelve-hour mark on the dial 17, the said pinion 15 is loosely mounted on the shaft 16, with which it is frictionally coupled by means of a coiled spring 20, encircling the shaft and interposed between a fixed collar 21, mounted thereon, and the inner face of the said pinion, the rear face of which bears against a corresponding fixed collar 22, also mounted on the shaft. A heart-shaped restoring-cam 23, rigidly secured to the rear end of the shaft, provides for turning it in one direction or the other within the pinion 15 against the tension of the said spring 20 when it is desired to restore the pointer 19 to zero, as will be described later on. The movement of the rated pointer 19 is compared by the timer with the movement of a rating-pointer 24, which accurately "portrays," so to speak, the action or beat of the timepiece to be rated. For convenience in distinguishing between the two pointers they are preferably differentiated from each other in design, length, and color, or in some manner, which will enable the timer to follow them with the least effort of his eye. As shown, the rating-pointer 24 is a trifle shorter than the rated pointer 19 and is located directly back of the same upon a socket 25, passing through the dial 17, loosely mounted upon the forward end of the shaft 16 and carrying a wheel 26, meshed into by a wheel 27, mounted upon the projecting forward end of a shaft 28, journaled in the frame-plates 2 and 3 and carrying a pinion 29, meshing into a wheel 30, mounted upon a shaft 31, journaled in the rear frame-plate 3, and extending forward through the front frame-plate 2 and journaled at its forward end in the plate 32 of a time-piece-holder, which may be varied in form and details of construction. At its projecting forward end the shaft 31 carries a pinion 33, which is meshed into by a wheel of the timepiece to be rated, and so accurately transmits the rate of that timepiece to the rating-pointer 24, the movement of which with re-

spect to the rated pointer 19, as the two pointers sweep over the face of the dial 17, will be more or less divergent, according to the timepiece to be rated is running at a rate more or less divergent from the standard 70 timepiece. In order that the shaft 28 may be turned in one direction or the other for restoring the rating-pointer 24 to its starting or zero position, I provide it with two fixed collars 34 and 35 and locate a coiled spring 36 75 between the collar 35 and the pinion 29, the rear face of which bears against the collar 34, the tension of the spring 36 being such that normally the pinion 29 will be coupled with the shaft to accurately transmit the action of 80 the timepiece to be rated to the rating-pointer 24. For the purpose of turning the shaft 28 in one direction or the other within the pinion 29 and against the tension of the spring 36 I locate a heart-shaped restoring-cam 37 at the 85 rear end of the shaft 28 and operate it simultaneously with the restoring-cam 23, as will be hereinafter described. The timepiece-holder, of which the plate 32 before mentioned is a feature, will be constructed with 90 reference to the size and character of the timepieces to be rated and will therefore obviously change in form.

The device shown in Figs. 1 to 7, inclusive, is "rigged," so to speak, for rating watches, 95 and the timepiece-holder is therefore constructed accordingly. The same device may be used to equal advantage in rating small clocks, in which event the timepiece-holder will be suitably modified and the wheel 33 100 replaced by a wheel suitable for coaction with a wheel of a clock-train. If desired, each device may have several interchangeable timepiece-holders to be used as called for by the timepieces to be rated. The said plate 32 is secured to the front face of the front frame-plate 2 by means of pillars 38, the ends of which receive screws 39. A narrow strip 40, conforming to the outline of the front movement-plate of the timepiece 41 to be 105 rated, is secured to the edge of the plate 32 and forms, as it were, a very shallow socket for the reception of the said front movement-plate, whereby the movement to be rated is not only held against edgewise displacement, 110 but has the fourth wheel 42 of its train located so as to be meshed into the pinion 33. Here I may add that it is not essential that the rate of the movement to be timed shall be taken from its fourth wheel, as it makes 115 no essential difference what wheel its rate is taken from. However, it will probably be the most convenient to transmit its rate to the rating-pointer 24 from its fourth wheel. The timepiece 41 of course may be of any 120 construction, and detailed illustration and description of its parts is thought to be wholly unnecessary. For binding it upon the plate 32 I employ a locking-lever 43, having a sleeve 44, embracing and turning upon 125

130

the lower pillar of the three pillars 38. This locking-lever is formed near its inner end with a locking-finger 45, which projects through an opening 46 in the plate 32 into 5 position to be engaged with the front movement-plate of the timepiece 41 to be rated. Near its outer end the lever 43 is formed with an operating-handle 47 and a long spring-finger 48, also adapted to be engaged with 10 the said front movement-plate. When the lever is pulled downward to the limit, its fingers 45 and 48 are retired into positions in which they clear the front plate of the movement 41, so as to permit the same to be 15 located within the centering-strip 40, after which the lever is lifted by its handle 47 and its fingers 45 and 48 engaged with the said plate, so as to firmly bind the movement in place. In order that the timer may keep 20 track of the time from the moment the rated and the rating pointers are started together, I by preference employ a minute-pointer 49, arranged to sweep a small minute-circle 50, corresponding in position on the dial 17 to 25 the minute-circle of an ordinary watch. As shown, the minute-circle 50 is provided with the numerals 1, 2, 3, and 4 and is swept once in four minutes by the minute-pointer 49.

Of course the minute-pointer may be made 30 to complete a revolution once in one minute or in any given number of minutes, as found most convenient; but the timer will rarely require more than four minutes in which to observe the differential performance of the 35 movement, being timed with respect to the performance of the standard timepiece. In ordinary practice one minute will be sufficient to show to the timer to what extent the time-piece being rated needs adjusting. Thus in 40 the device shown a variation of one second in two minutes will appear to be a variation of six minutes upon the rated dial, resulting from speeding up the rated and rating pointers by appropriate gearing, so as to magnify 45 the actual speed of the train of the rating device and the actual speed of the timepiece to be rated, whereby the variation between the speed of the rating device and the time-piece to be rated is correspondingly magnified and made manifest to the eye of the 50 timer. This example will be sufficient to show how "magnified," so to speak, in my device is the differential running of the two timepieces. The minute-pointer 49 is mounted upon the projecting forward end of a minute-shaft 51, journaled in the frame-plates 2 and 3 and carrying a pinion 52, meshing into the third wheel 53 of the standard timepiece, the pinion 52 being frictionally coupled with the shaft 51 by means of a spring 54 and the pinion and spring being interposed between two fixed collars 55 and 56 on the said shaft. To provide for restoring 55 the minute-pointer 49 to its starting or zero position, the rear end of the shaft 51 is furnished with a heart-shaped restoring-cam 57, Fig. 6, through the medium of which the shaft 51 is turned one way or the other within the said pinion 52 against the tension of its spring 54, as will be more fully described 60 later on. The restoring-cams 23 and 37 are simultaneously operated upon for respectively restoring the rated pointer 19 and the rating-pointer 24 to their starting or zero positions by means of a vertically-movable 65 restoring-slide 58, having a finger 59 for coaction with the cam 23 and a finger 60 for coaction with the cam 37 and formed with slots 61 and 62, receiving shoulder-rivets 63, by means of which the slide is movably connected with the inner face of the back frame-plate 3. At its upper end the slide is furnished with a push-button 64, by means of which it is manually operated. At its lower end the slide is engaged with the short arm 70 75 of a bell-crank lever turning upon a stud 66 and having its long arm 67 furnished at its upper end with an inwardly-turned hook 68, having a finger 69 for coaction with the restoring-cam 57 aforesaid. A spring 70, connected at one end with the plate 3 and at its opposite end with the said arm 67, normally maintains the said bell-crank lever and slide 58 in their retired positions, in which the bell-crank lever is swung from left to right and 80 the slide lifted. No matter what the positions of the pointers 19, 24, and 49 may be at any given time, they will all be restored to 85 their starting positions, so as to start off together by pushing down upon the push-button 64, whereby the cam 23 will be engaged by the finger 59, the cam 37 by the finger 60, and the cam 57 by the finger 69 and the cams brought into corresponding positions with 90 their vertical axes in vertical planes. As 95 these cams are rigidly secured, respectively, to the rear ends of the shaft 16, the shaft 28, and the minute-shaft 51, the same will be turned one way or the other within the respective pinions 15, 29, and 52 against the 100 tension of the respective springs 20, 36, and 54, whereby the wheels into which the said pinions are meshed are not disturbed. 105

In using my improved device to time a watch the same is applied to it as described 110 and the two pointers started off in unison. Their divergence from each other, be it great or small, as they rapidly sweep over the rated dial 17 will show almost instantaneously to the timer just what adjustment of the 115 hair-spring of the watch being timed is required to make it perform so nearly in unison with the performance of the standard time-piece that it will be safe to rely for its final regulation upon its own special regulator 71 120 or equivalent device. When the watch is being timed, its regulator is preferably set midway or about midway of its two extreme positions. 125

In the modified form of my device shown 130

by Figs. 8 to 10, inclusive, the rated pointe 19^a and the rating-pointer 24^a, instead of being arranged to rotate upon one axis and sweep over one dial, turn upon separate axes over separate dials 72 and 73, placed side by side and secured to the upper portion of a front frame-plate 74, secured by pillars 75 and screws 76 to a corresponding back frame-plate 77. The rated pointer 19^a is mounted upon the projecting forward end of an arbor 78, journaled in the plates 74 and 77 and carrying a wheel 79, frictionally coupled with it by a spring 80 and meshing into a wheel of and driven by a standard timepiece. (Not shown.) At its rear end the arbor 78 is furnished with a restoring-cam 81 for restoring the pointer 19^a to its starting position. The rating-pointer 24^a is mounted upon the projecting forward end of an arbor 82, journaled in the plates 74 and 77 and carrying a wheel 83, frictionally coupled to it by a spring 84 and meshing into a wheel 85, carried by an arbor 86 and in turn meshing into a wheel 87, carried by an arbor 88, which projects forward through the front plate 74 and has bearing at its forward end in a plate 89, provided for supporting the timepiece to be rated, the projecting forward end of the shaft 88 being furnished with a wheel 90, meshing into and driven by a wheel or pinion of the timepiece to be timed and corresponding to the wheel 33 of the construction previously described. The shaft 82 is provided at its rear end with a heart-shaped restoring-cam 91, by means of which it is turned in either direction within the wheel 83 for restoring the pointer 24^a to its starting position. Light springs 92 and 93, secured by posts 94 to the inner face of the frame-plate 74, respectively engage with the arbors 78 and 82 and steady the operation of the pointers 19^a and 24^a, though this is not necessary, especially if the teeth of the several wheels are properly cut. For simultaneously restoring the pointers 19^a and 24^a to their starting positions I employ a slide 95, furnished at its upper end with a push-button 96 and having slots 97, receiving shoulder-rivets 98, by means of which the slide is attached to the inner face of the frame-plate 77. The said slide is formed with two arms 99, respectively arranged to simultaneously engage the cams 81 and 91, whereby the same are brought into corresponding positions in vertical planes when the slide is pushed to the limit of its downward movement against the tension of its spring 100, the upper end of which is attached to the upper shoulder-rivet 98, while its lower end is attached to a pin 101 in the lower end of the slide. This spring normally holds the arms 99 clear of the cams 81 and 91. The plate 89, which corresponds to the plate 32 before described, is secured to the frame-plate 74 by means of pillars 102 and screws 103 and furnished with two pins 104 105, arranged to en-

ter holes in the front plate of the movement to be rated, whereby the same is held against edgewise movement on the plate 89, to which it is clamped by a locking-lever hung on a stud 106, and comprising a clamping-arm 107 and an operating-handle 108; but the particular means employed for supporting the timepiece to be rated in position for the transmission of the action of its train to the rating-pointer 24^a may obviously be widely varied. The mode of using the device just now described is just the same as the mode of using the device first described, the only difference between the two devices being that the rated and rating pointers sweep over separate dials.

In view of the modification described and of others which may obviously be made I would have it understood that I do not limit myself to the construction herein set forth, but hold myself at liberty to make such departures therefrom as fairly fall within the spirit and scope of my invention.

It will be observed that both of the mechanisms shown and described are complete in themselves or self-contained and that both are non-electric in their character. In using either mechanism the running of the timepiece to be rated too slow or too fast is magnified and displayed, as it were, before the eye of the timer, who must then use his judgment in manually adjusting the timepiece to be rated—as, for instance, by shortening or lengthening its hair-spring in order to correct its speed. After so adjusting the timepiece to be rated the two timepieces are manually synchronized preparatory to another trial, which shows the effect of the adjustment, and so on.

Having fully described my invention, what I claim as new, and desire to secure by Letters Patent, is—

1. In a rating device for timepieces, the combination with a frame adapted to temporarily receive and position the timepiece to be rated, of a standard timepiece mounted in the said frame, a rated pointer driven by the said standard timepiece, a rating-pointer arranged to have its movement visually compared with that of the rated pointer, and means carried by the said frame for mechanically transmitting to the rating-pointer the action of the timepiece to be rated when the same is positioned with respect to the said frame.

2. In a rating device for timepieces, the combination with a frame adapted to temporarily receive and position the timepiece to be rated, of a standard timepiece mounted in the said frame, a rated pointer driven by the said standard timepiece, a rating-pointer arranged to have its movement visually compared with that of the rated pointer, means carried by the said frame for mechanically transmitting to the rating-pointer the action

of the timepiece to be rated when the same is positioned with respect to the said frame, and manual means for simultaneously restoring the said rated and rating pointers to their starting or zero positions.

5 3. In a rating device for timepieces, the combination with a frame, of a standard timepiece mounted in the said frame, a rated pointer driven by the said standard timepiece, a rating-pointer arranged to have its movement visually compared with that of the rated pointer, a timepiece-holder applied to the said frame for temporarily receiving and positioning the timepiece to be rated, and means carried by the said frame for mechanically transmitting to the rating-pointer the beat of the timepiece to be rated when the same is positioned in the said holder.

10 4. In a rating device for timepieces, the combination with a frame adapted to temporarily receive and position the timepiece to be rated, of a standard timepiece mounted in the said frame, a rated pointer driven by the said standard timepiece, a rating-pointer, means carried by the said frame for mechanically transmitting to the rating-pointer the beat of the timepiece to be rated when the same is positioned with respect to the said frame, and manually-operated restoring-cams for simultaneously restoring the said rated and rating pointers to their starting or zero positions.

15 5. In a rating device for timepieces, the combination with a standard timepiece, of a rated pointer driven thereby, a dial over which the said pointer sweeps, a rating-pointer turning upon the same axis as the rated pointer and also sweeping over the said dial, and means for transmitting to the rating-pointer the beat of the timepiece to be rated.

20 6. In a rating device for timepieces, the combination with a standard timepiece, of a rated pointer driven thereby, a dial over which the said pointer sweeps, a rating-pointer turning upon the same axis as the rated pointer and also sweeping over the said dial, means for transmitting to the rating-pointer the beat of the timepiece to be rated, and a minute-pointer for registering the revolutions of the rated and rating pointers over the dial.

25 7. In a rating device for timepieces, the combination with a frame adapted to temporarily receive and position the timepiece to be rated, of a standard timepiece mounted in the said frame, a rated pointer driven by the said standard timepiece, a rating-pointer arranged to be compared in its action with the action of the rated pointer, and gearing carried by the said frame for mechanically transmitting the beat of the timepiece to be rated to the rating-pointer when the timepiece to be rated is positioned with respect to the said frame.

30 8. In a rating device for timepieces, the combination with a frame, of a standard timepiece mounted therein, a rated pointer driven thereby, a rating-pointer arranged to have its movement readily compared with that of the rated pointer, means for securing the timepiece to be rated to the said frame, and gearing for transmitting the beat of the timepiece to be rated to the said rating-pointer, the said means including an arbor projecting forward from the said frame and through the said means for supporting the timepiece to be rated.

35 9. In a rating device for timepieces, the combination with a frame, of a standard timepiece mounted therein, a rated pointer driven thereby, a rating-pointer arranged to be compared in its action with that of the rated pointer, a timepiece-holder applied to the said frame, a locking-lever coacting with the said holder for binding the timepiece to be rated thereto, an arbor projecting forward through the said holder and carrying a pinion arranged to engage with one of the wheels or pinions of the timepiece to be rated, and gearing connecting the said arbor with the rating-pointer.

40 10. In a rating device for timepieces, the combination with a frame adapted to temporarily receive and position the timepiece to be rated, of a standard timepiece mounted in the said frame, a rated pointer driven by the said standard timepiece, a rating-pointer arranged to be visually compared in its action with that of the rated pointer, means carried by the said frame for mechanically transmitting to the rating-pointer the beat of the timepiece to be rated when the same is positioned with respect to the said frame, and a restoring-slide connected with the said rated and rating pointers for manually restoring the same to their starting or zero positions.

45 11. In a rating device for timepieces, the combination with a frame adapted to temporarily receive and position the timepiece to be rated, of a standard timepiece, a rated pointer driven thereby, a rating-pointer, means for mechanically transmitting to the rating-pointer the beat of the timepiece to be rated, and manual means for synchronously restoring the said pointers to their starting positions, the pinions driving the said rated and rating pointers being frictionally coupled with their arbors which may be turned within them one way or the other for restoring the pointers to their starting positions.

50 12. In a rating device for timepieces, the combination with a frame having front and rear plates, of a standard timepiece located between the said plates, a dial secured to the said front plate, a rated pointer sweeping over the said dial and driven by the said standard timepiece, a rating-pointer arranged to be visually compared in its action with that of the said rated pointer, a time-

piece-holder secured to the said front frame-
plate for temporarily receiving and position-
ing the timepiece to be rated, and mechan-
ical means carried by the said frame for
transmitting the beat of the timepiece thus
positioned to the said rating-pointer.

In testimony whereof I have signed this

specification in the presence of two subscrib-
ing witnesses.

WILSON E. PORTER.
